CLAIM

The ornamental design for a conversion tray for media storage container, as shown and described.

DESCRIPTION

FIG. 1 is a perspective view of a conversion tray for media storage container showing our new design;

FIG. 2 is a top plan view thereof;

FIG. 3 is a bottom plan view thereof;

FIG. 4 is a left side view thereof;

FIG. 5 is a right side view thereof;

FIG. 6 is a rear elevation view thereof; and,

FIG. 7 is a front elevation view thereof.

The broken line showing is included for the purpose of illustrating environmental structure and forms no part of the claimed design.
